UNITED STATES PATENT OFFICE.

EARL S. BURDICK, OF MILWAUKIE, OREGON.

RADIAL LOCK.

Application filed October 29, 1921. Serial No. 511,329.

To all whom it may concern:

Be it hereby known that I, EARL S. BURDICK, a citizen of the United States, and a resident of Milwaukie, in the county of 5 Clackamas and State of Oregon, have invented a new and useful Radial Lock, of which the following is a specification.

This invention relates more particularly to locks which are secured to doors and 10 which are controlled by the united action of a key and a coin.

The objects of my invention are to provide an exceedingly simple and efficient lock adaptable to many different purposes, especially for lockers or rented compartments or 15 garages in which the user purchases a key by inserting a coin and can unlock the lock only by inserting and surrendering his key.

A further object is to so construct my 20 lock as to eliminate a large percentage of the friction ordinarily encountered in locks of this nature which render the power required to operate them an extremely variable quantity.

25 A still further object is to produce a lock in which the combination can readily be altered to correspond with a given key without necessitating the elaborate or expensive equipment for duplicating a key which may 30 be missing, or removing and replacing a combination to protect against stolen keys.

Another object is to provide a key which 35 cannot be inserted into the key hole in the wrong manner and cannot be inserted into another locker key hole at all.

I accomplish these results in the manner set forth in the following specification and 40 illustrated in the accompanying drawings, in which:

45 Figure 1 is a section looking at the lock from the rear showing the cover and actuating disk removed and showing the parts in the unlocked position. Figure 2 is a view similar to Fig. 1 showing the cover removed and a portion of the actuating disk cut away with the parts in the locked position. Figure 3 is a section along the line 3—3 in Fig. 1. Figure 4 is a section along the line 4—4 in Fig. 2. Figure 5 is a side elevation 50 from the bolt side of Fig. 1. Figure 6 is a section along the line 6—6 in Fig. 1. Figure 7 is a section along the line 7—7 in Fig. 2. Figure 8 is a front elevation showing the

bolt actuating spring of which Figure 9 is a side elevation. Figure 10 is a front elevation of a key of which Figure 11 is a plan and Figure 12 a side elevation. Figure 13 is a front elevation of a modified form of key of which Figure 14 is a side elevation. Figures 15 and 16 are plan views of other 55 modifications of the key. Figure 17 is a front view of the adjustable key hole mechanism of which Figure 18 is a side elevation shown in section. Figure 19 is a front view of a group of parts including a key during 60 the unlocking operation. Figure 20 is an end elevation of a portion of Fig. 19, showing an adjustable plunger and the manner in which it is prevented from getting out of 65 alinement.

70 Similar numbers of reference refer to the same or similar parts throughout the several views.

75 Referring in detail to the drawings, I have chosen to illustrate my device as attached to the plate 30 which may act as the hinged portion of a door. Secured on the plate 30 is a second plate 31 which forms one side of the frame for the lock. The walls 32 form a box with the plate 31 and contain all of 80 the parts of the lock which are covered with a cover-plate 33. A handle 34 is secured to the shaft 35 which passes through the plates 30, 31 and 33. Rotatably mounted on the hub 36, which is secured to the inner side of 85 the plate 31, is a bolt disk 37 which has formed on its periphery a projecting bolt 38 which swings outside of the wall 32 when the disk 37 is rotated on its axis. This bolt is slightly offset from the central portion of 90 the bolt disk. The side 39 of the bolt 38 is almost radial and extends the full length of the offset portion of the bolt. A second projecting member 40 is also offset from the bolt disk 37 and the space between the members 38 and 40 is utilized to receive the coin as it 95 is deposited for the purchase of a key.

100 On the inner side of bolt 38 I have secured a curved fork 41 of thin material flush with the inner side of the bolt 38. The slot in this fork is an arc struck from the center of the shaft 35. A curved slot 42 also struck from the center of the shaft 35 is cut through the bolt disk 37 and contains a curved table 43, which is secured to 105 the inner side of the plate 31. The table

43, however, does not occupy the full length of the slot 42. It is upon this table 43 that the coin 44 rests when inserted by the purchaser through the guide 45 whose upper end terminates in the recess 46. Secured to the inner side of the bolt disk 37 is a coin guide 47 and the key guides 48 and 48^A and below the coin receiving portion of the bolt disk 37 is formed a coin receptacle 49 to which access may be secured from the outside by an authorized attendant through a combination lock, or through any other locking device. Below the key guides 48 and 48^A is a key ejecting chute 50 having an open access to the exterior of the lock.

Above the table 43 is also placed a key receiving chute 51 whose upper end is provided with a slidable opening 52^A having a plurality of lugs 53 attached thereto and which may be held in any position by means of the screws 54 in the plate 31. The lower end of the key receiving chute 51 is just wide enough to permit the passage of the key 52 freely and allow same to rest upon the table 43.

Pivoted on the same screw 54^A are three arms 55, 56 and 57 which are held against the stop 58 by the springs 59. Each of these arms contains a slot 60 which is an arc struck from the center of the shaft 35 when the arms 55, 56 and 57 are held a fixed distance away from the stop 58.

A third projection 61 on the bolt disk 37 engages one side of the key 52 as it rests on the table 43. On the outer side of the projection 61 is formed a stud 62 which is adapted to ride in the curved slots 60 of the three arms 55, 56 and 57 when they are in the proper position. If they are not properly positioned then the lug 62 will strike either of the surfaces 63 and prevent the bolt disk 37 from rotating in an unlocking direction.

Referring more particularly to the key itself it will be observed that I have illustrated a somewhat rectangular key 52 having a curved base 64 and curved steps 65, 66 and 67 formed on its upper side and that on its rear side are a number of grooves 68 which correspond with the lugs 53 on the member 52^A.

It will be observed that the corners 69 of the steps 65, 66 and 67 are slightly rounded and that it is preferable to round all of the corners of the key slightly to prevent wear in the pockets of the carrier.

In order to move the arms 55, 56 and 57 the amount required to enable the lug 62 to enter the slots 60 I have slidably attached to each of the arms a plunger 70 which is held in its angular relation to its arm by means of the turned edge 71 and is held against sliding after being properly positioned by means of the screw 72 which is locked by the nut 73. The corners 69 are

rounded slightly in order to enable the motion of the key 52 to raise each of the plungers 70 to a height which will permit it to ride upon its respective step 65, 66 or 67 which, being a fixed distance, determines accurately the position of the curved slot 60, as shown in Fig. 19, by the interposition of the key 52 on the table 43.

It will be observed that I have also illustrated a number of modifications of this key, such as the rectangular key in Figures 13 and 14, and the keys shown in Figures 15 and 16 having circular and dove-tailed grooves 74 and 75 which, of course, would require a corresponding lug 53. The grooves 74 and 75 are used to prevent easy duplication of the key, for instance by a casting process.

Secured on the shaft 35 is a bolt actuating disk 76 which has an offset projection 77 the same shape and size as is the projection 40 on the bolt disk 37. This projection 77 carries a lug 78 adapted to ride in the slot of the member 41, and if a coin 44 is in the way to engage same and to transfer its motion to the bolt disk 37 causing the bolt 38 to take the position shown in Fig. 2. The face 79 of the projection 77 engages the key 52 when rotating in the opposite or unlocking position and moves it along on the table 43.

In Figures 8 and 9 I have illustrated a spring mechanism which consists of a plunger 81 which is attached to the bolt disk 37 by means of the pin 82. The lower end of the plunger 81 carries a compression spring 83 and rides in the slotted bracket 84 which is secured to the plate 31. These parts are omitted in Figures 1 to 7 to avoid complication and their relation to the lock is shown only in Figures 8 and 9.

The function of these parts is to cause the bolt 38 to make a complete throw whenever it passes over the center of its travel.

The operation of my device is as follows: When an individual desires to check his suitcase in a locker equipped with one of these devices he merely inserts his coin in the chute 45 and rotates the handle 34. Acting through the coin 44 the lug 78 rotates the bolt disk to the position shown in Fig. 2, at which point the coin drops off of the table 43 and falls into the receptacle 49. The key 52, which rests upon the table 43, is at the same time moved along by the member 48 until it falls off of its table 43 into the key ejecting chute 50 and is delivered to the purchaser, who carries it away with him.

Upon attempting to unlock this locker the same key, which cannot be inserted into any other lock owing to the grooves on its back, is placed in the key chute 51 and rests on the table 43. The handle 34 now being turned on the opposite direction the face 79 on the projection 77 engages the key 52 and slides same along the table 43.

The corners 69 of the key steps 65, 66 and 67 each engage one of the plungers 70 and turn the arms 55, 56 and 57 on the pivot 54^A. When the proper key has been inserted a 5 continued movement of the lever 34 and its attached parts causes the key 52 to fall off of the table 43 and rest upon the table 80 where it is ready for the next user of the lock.

In event that a key is lost or stolen the 10 caretaker merely secures a new one, adjusts the key hole to permit its insertion into the lock and adjusts the plungers 70 so that they will rest upon their respective steps when the lug 62 is in or about to enter the slot 60. 15 The screws 72 are then tightened and the lock ready for use.

It is evident that by this method the individual combinations may be altered as often as desired and that the danger of anyone 20 placing his key in the wrong locker and possibly causing him to miss a train from the entailed delay will be entirely eliminated.

It will be understood that it is desirable in the production of the keys 52 that the 25 grooves 68 are never spaced equi-distant from the center of the key, as this will prevent any possibility of the key being inserted wrong end foremost in the key slot.

While I have thus illustrated and 30 described my invention it is not my desire to limit myself to this precise form or method of application, but intend that it shall cover all forms and modifications that fall fairly within the appended claims.

35 What I claim is:

1. A lock having a frame, a radial bolt pivoted on said frame, a coin-containing recess formed within said bolt, a curved table secured to said frame forming a bottom for 40 said recess, and a rotatable bolt actuating arm adapted to engage said coin in a manner to move said bolt to a locked position and to release said coin at the completion of the locking travel of said bolt thereby removing any operating action between said bolt and arm.

2. The combination of a lock having a frame, a radial bolt pivoted on the inside of said frame, a coin-containing recess formed 50 in said bolt, a curved table forming a bottom for said recess, a rotatable bolt actuating arm adapted to engage said coin in a manner to move said bolt and to release said coin at the completion of the locking travel of said bolt, and a key adapted to lock said arm to said bolt in a manner to withdraw said bolt and to release said key after the complete withdrawal of said bolt.

3. A lock having a frame, a rotatable bolt 60 disk pivoted in said frame having a coin-containing slot in said disk, a curved table on said frame adapted to support a coin in said slot, an arm pivoted on the same axis as is said bolt and having a coin-engaging finger projecting from said arm, a key-con-

taining slot in said disk whose bottom is also formed by said curved table, a stud projecting from said disk, a plurality of arms pivoted on said frame each of which has a curved slot adapted to receive said projecting stud when properly positioned by a key, a key adapted to ride in said rotatable disk on said curved table, and an adjustable plunger on each of said slotted arms adapted to engage said key and to be actuated thereby.

4. An adjustable combination lock having a rotatable bolt carrying disk, a lug projecting from said disk, a plurality of slotted tumbler arms pivoted beside said disk and adapted to receive said lug within their slots when properly positioned, and a key adapted to be carried by said rotatable bolt disk and to engage the various tumblers and actuate same in a manner that said slots will 85 register with said lug.

5. A rotatable bolt disk having coin-containing and key-containing recesses formed therein, a stationary curved table forming a bottom for said recesses during parts of 90 their travel, means for rotating said disk by pressing a coin against one side of its recess in a manner to project said bolt, means for withdrawing said bolt by reversing the movement of said disk consisting of a key placed within said key recess upon 95 said curved table, means for moving said key against one side of its recess until said bolt is withdrawn, means for locking said disk against rotation by an improper key 100 consisting of a stud projecting from said disk, a plurality of slotted arms alongside of said disk in the path of said stud, adjustable plungers on said slotted arms adapted to permit the registration of said slots with said stud when said plungers are 105 actuated upon by a given key, and an adjustable key slot adapted to permit said slot also to conform with said given key.

6. A key for coin controlled locks consisting of a flat plate having parallel sides, a concave base, steps formed on one side of its upper portion perpendicular to its sides, and a plurality of grooves formed in the back of said key perpendicular to said steps.

7. A key for coin controlled locks consisting of a flat plate having parallel sides, concentric base and step members formed at one side of its top, and a pair of grooves formed in the back of said key parallel to its sides.

8. In a lock, the combination of a front and back plate member having an operating handle mounted on a shaft which passes through both plates and having a hub on the inside of the front plate around said shaft with a rotatable bolt disk mounted on said hub, a curved table secured on the inside of said front plate and passing through said bolt disk, a coin chute leading from the 125

front of said front plate to the top of said table, a key chute leading from the front of said front plate to the top of said table, an arm secured to said shaft adapted to press against a coin in one direction when on said table or against a key upon said table in the opposite direction, means for

holding said bolt disk against rotation consisting of a lug secured to said bolt disk, a plurality of pivoted tumblers each of which has a curved slot adapted to receive said lug when said tumblers are properly positioned by engagement with said key. 10

EARL S. BURDICK.
